CLAIM

We claim the ornamental design for a portable electronic device, as shown and described.

DESCRIPTION

FIG. 1 is a front left perspective view of a portable electronic device showing the new design;
FIG. 2 is a front view thereof;
FIG. 3 is a rear view thereof;
FIG. 4 is a right side view thereof;
FIG. 5 is a left side view thereof;

FIG. 6 is a top view thereof;
FIG. 7 is a bottom view thereof; and,
FIG. 8 is a front right perspective view thereof.
The short dash-short dash lines represent portions of the portable electronic device that form no part of the claimed design. The short dash-long dash lines are boundary lines which do not form part of the claimed design.

UNITED STATES PATENT AND TRADEMARK OFFICE
CERTIFICATE OF CORRECTION

PATENT NO. : D750,061 S
APPLICATION NO. : 29/449307
DATED : February 23, 2016
INVENTOR(S) : Shanshan Li et al.

Page 1 of 1

It is certified that error appears in the above-identified patent and that said Letters Patent is hereby corrected as shown below:

On the Title Page

In Item (74), Name of the Attorney, in Column 2, Line 1, delete "Lidenbaum" and insert
-- Lindenbaum --, therefor.

Signed and Sealed this
Fourteenth Day of February, 2017

Michelle K. Lee
Director of the United States Patent and Trademark Office
